FIRING MEANS FOR WELL PERFORATING GUNS

Arthur J. Collins, Corpus Christi, Tex.

Application February 9, 1940, Serial No. 318,050

12 Claims. (Cl. 164—0.5)

This invention relates to new and useful improvements in a firing means for a well perforating gun.

This application is a continuation in part of my original application, filed July 19, 1939, Serial Number 285,415, and is substituted therefor.

One object of the invention is to provide an improved firing head having positive means for firing a gun.

An important object of the invention is to provide an improved head, having spring-operated means, normally held in its raised position so that said gun cannot be accidentally fired.

An important object of the invention is to provide an improved head which is actuated by the rotation of the suspension tubing.

A further object of the invention is to provide an improved head wherein the firing mechanism is rigidly held so that the same is unable to fire the gun until the suspension means has been rotated a predetermined number of times.

A further object of the invention is to provide an improved head wherein said gun may be accurately located within the casing and may be handled with comparative safety above the ground and in the ground.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a vertical view, partly in section and partly in elevation, of a firing head constructed in accordance with the invention.

Figure 2 is a vertical cross-sectional view, showing the lower portion of the head attached to a gun.

Figure 3 is a horizontal cross-sectional view taken on the line 3—3 of Figure 1.

Figure 4 is a horizontal cross-sectional view taken on the line 4—4 of Figure 1.

Figure 5 is a horizontal cross-sectional view taken on the line 5—5 of Figure 2.

Figure 6 is a vertical view, partly in elevation and partly in section, of the upper portion of the head, showing it in its hammer-releasing position.

Figure 7 is a vertical view, partly in elevation and partly in section, showing another form of the head constructed in accordance with the invention,

Figure 8 is a view, similar to Figure 7, which shows the hammer in its released position.

Figure 9 is a horizontal cross-sectional view taken on the line 9—9 of Figure 7.

Figure 10 is a horizontal cross-sectional view taken on the line 10—10 of Figure 7.

Figure 11 is a horizontal cross-sectional view taken on the line 11—11 of Figure 7.

Figure 12 is a horizontal cross-sectional view taken on the line 12—12 of Figure 7.

Figure 13 is a vertical cross-sectional view of another form of the invention.

Figure 14 is a view, similar to Figure 13, showing the hammer in its released position, and

Figure 15 is a horizontal cross-sectional view taken on the line 15—15 of Figure 13.

In the drawings, the numeral 10 designates a sectional head. The lower section 11 has its lower end 12 internally screw-threaded to form a box, and above said box there is provided an axial cylindrical chamber 13. A hammer 14 is slidably mounted within said chamber. The hammer, near its upper end, is provided with an external annular groove 15. The lower end of the chamber 13 is closed by an upstanding stud 16 of a gun barrel 17. The upper end of said chamber is terminated within the section 11; thus the hammer is slidably confined between the closed upper end and the closed lower end of the chamber 13. A coiled spring 18 is confined between the upper end of the hammer 14 and the upper closed end of the chamber 13; said spring, when compressed, will act to urge said hammer downwardly.

The hammer 14 is constructed with an axial recess 19, and a plurality of divergent vents 20 extend to the bottom of the hammer and communicate with the chamber 13. Thus an air cushion cannot be formed within the chamber 13 below the hammer, thereby preventing air or fluid from becoming trapped within the path of the hammer when it is moved downwardly by the spring 18. The section 11 is provided with an upper axial bore 21 which has its upper end 22 internally screw-threaded and its lower end spaced above the chamber 13. A plurality of radial ports 23 extend from the bore 21 to the outer surface of the head. A tubular mandrel 24 has its lower end 25 externally screw-threaded and screwed into the upper internally screw-threaded end 22 of the bore 21. Surrounding and slidably engaging around the mandrel 24, is the upper portion of the head 10. Said portion is divided into a sectional sleeve, having an upper section 26 and a lower section 27. The lower

end of the section 27 is externally screw-threaded, and a collar 28 is screw-threadedly attached to said lower end of the section 27. Said collar projects below the lower end of the sleeve and is provided with an inwardly extending annular flange 30. Rotatably confined between the lower end of the section 27 and the upper surface of the flange 30, is a ring 31 which surrounds the mandrel 24. However, said ring is free to rotate around the mandrel and between the section 27 and the flange 30.

A plurality of rods 32 are mounted so as to slide vertically within the section 11 on each side of the bore 21, and to extend below said bore. The upper ends of said rods are securely fastened to the ring 31. The lower end of the section 11 is provided with diametrically opposite openings 33, extending from the chamber 13, and which have their outer ends internally screw-threaded. Screw-threaded plugs 34 close the outer ends of the openings 33, but do not contact the rods 32. Positioned between the rods 32 and the hammer 14, are a pair of balls 35 which are normally held in the annular groove 15 of the hammer 14 by the rods 32. The rods 32 are of such a thickness that said balls are held within said groove and cannot escape until said rods are pulled upwardly, thereby allowing said balls to move out of said groove. Thus said hammer is held in its elevated or firing position when the spring 18 is compressed, whereby the hammer is ready to be released for firing.

When the rods 32 are moved upwardly so that the lower ends pass the balls 35, said balls are then free to move inwardly and thus release the hammer. The lower ends of the rods 32 are each cut on its inner side to form a wedge 36, so that when said rods are moved downwardly, the wedges 36 will engage the balls 35 and move them inwardly to engage within the groove 15 and lock the hammer. The upper end of the sleeve section 27 is provided with an upwardly tapered bowl 37. Surrounding the mandrel 24, and engaging within the bowl 37, is a split nut 38 which has its outer surface tapered correspondingly to the bowl 37, and its inner surface screw-threaded. To hold the nut against rotation, a key 40, embedded in the bowl, engages in the split or gap of said nut.

A portion 39 of the outer surface of the mandrel 24 is provided with screw-threads, equal in number to the screw-threads of the nut 38, and which match with the screw-threads of said nut. The screw-threads are of a saw-tooth or ratchet cross-section so as to permit the mandrel to be moved upwardly through said nut, when the nut is elevated in the bowl, sufficiently to permit the bowl to yield, whereby the threads may pass each other. When said nut is moved upwardly into the enlarged portion of the bowl 37, it will be free, and may spread so that the threads will not be in constant engagement and will not act to screw said mandrel downwardly; but, as said threads engage, the nut will spread and snap over the threads of the mandrel. However, when said nut is down within the taper 37, and the taper is urging the nut inwardly, said threads will be engaged; thus allowing the mandrel 24 to be screwed down through the sections 26 and 27.

Bowed friction springs 41 have their lower ends fastened on the lower portion of the sleeve section 27, so as to engage and ride upon the inner surface of the casing C and to hold the sleeve against rotation. The upper ends of the springs

engage within vertical grooves 42 at the upper end of the section 26 to permit the springs to elongate and yield inwardly. A safety plug 43 is inserted in the lower end of the member 11, and has its inner end underlying the hammer 14, said pin being left within the gun until such time that it is desired to be run into a well. At that time said pin is removed so as to allow the hammer to move downwardly when the balls are removed from the grooves 15 of said hammer.

In the drawings, there has been shown the gun body 17, which is one means of carrying forth the invention. The firing means will operate this gun or any other suitable gun. The gun shown in Figure 2 has a barrel 44. Said barrel is preferably cylindrical and is provided with a plurality of elongated transverse recesses or firing chambers 45 extending inwardly toward the center of said body. It is pointed out that said chambers are preferably cylindrical in shape and constitute a plurality of firing chambers so that cartridges or explosive charges may be inserted therein.

The stud 16 is provided with a central recess 46. The upper portion of said recess is enlarged and receives an elongated firing plunger 47. Surrounding the upper portion of the firing plunger is an annular collar 48. Confined between said collar and the lower end of the enlarged portion, is a coiled spring 49. The lower end of the plunger 47 extends downwardly into the reduced portion of said recess, and the upper end of said plunger extends above the stud and is surrounded by a retaining plug 50, which is screw-threaded into the upper portion of the enlarged portion of said recess. The plunger is slidable within the retaining plug and within the recess. An axial channel 51 extends throughout the barrel 44, and the lower end of said barrel receives a bull-nose plug 52. It will be noted that said plug closes the lower end of the channel 51. The channel 51 communicates or transacts with all of the chambers 45; said chambers being preferably spaced an equal distance apart, and forming a plurality of firing chambers.

Mounted in the channel 51, are a plurality of firing pins 53 which are disposed to slide longitudinally in said channel, which provides a guideway therefor. The pins 53 extend from one chamber to the next chamber, and have their ends terminated substantially at the bores of said chambers. The upper pin is the initial firing pin, and has its lower end terminating at the upper chamber, and its upper end projecting slightly into the enlarged recess 46 and underlying the lower end of the firing plunger 47. Any suitable cartridge or explosive 54 may be used.

In operation, the mandrel 24 is connected into the upper end 22 of the chamber 21. The hammer 14 is inserted within the chamber 13, and is pushed upwardly against the tension of the spring 18 and a safety pin 43 inserted so that said hammer cannot move downwardly. The balls 35 and the rod 32 are inserted, and the balls will engage within the annular groove 15. Thus the hammer is held in position by the safety pin while the balls are being inserted, and the device is then assembled. The pins 53 are inserted in the channel 51, and the cartridges 54 are inserted within the firing chambers 45. A jacket 55 is inserted over the barrel of the gun, and is screw-threadedly attached to the lower end of the member 11. Said jacket acts to cover and enclose the cartridges within the firing chambers 45; thus making a watertight gun bar-

rel. The device is then run into a well casing which is desired to be perforated.

A plurality of sections of pipe (not shown) are connected to the upper end of the mandrel 24, and by the use of the pipe or tubing, the gun barrel 44 may be stopped opposite the strata to be perforated. By running on a tubing, the barrel may be stopped more accurately than if the same had been run on a wire line. In other words, the stretch of a tubing can be determined, and is much less than the stretch of a wire line. While the device is being run into the well, the bottom portion may rotate, as it often does when running tubing in a well bore. As the lower end of the gun would rotate, the mandrel 24 would travel down through the nut 38 due to the screw-threaded engagement. If there was no way to reset the nut 38, the gun might fire before it reached its predetermined destination.

In order to reset the gun, the mandrel 24 is pulled upwardly, the nut 38 striking the lower end of the section 26, allowing the threaded portion 39 of the mandrel 24 to slide through said nut and snapping it apart as the threads push the threads of the nut outwardly until the upper end of the section 11 strikes the flange 30. In running the device, the tubing is made up as it is lowered into the well. In other words, a section of tubing is attached to the structure and is lowered into the well until the upper end of that section of tubing is near the top of the floor of the derrick. At that time slips are placed around said tubing to hold the same up while the traveling block is released, and is raised to the top of the derrick to pick up another section of pipe. Said section is then connected to the pipe already in the well. It is necessary to slightly raise the pipe within the well to release the slips, and at this time the mandrel 24 will also move up and reset with relation to the nut 38. This is 40 repeated until the tool has reached the strata which is desired to be perforated.

The operator has, previously to the time of running the gun into the well, predetermined by the coarseness or fineness of the threaded portion 39 of the mandrel 24, and the threads of the nut 38, the number of turns needed on the mandrel 24 to fire the gun. For example, he has set said gun so that it will take six turns to fire it. By rotation of the mandrel 24, the threads of the mandrel and the nut 38 will allow the mandrel 24 to move downwardly through the sections 26 and 27. In order to prevent the nut 38 from riding up the taper, a portion of the weight held at the top of the well is slackened off so that the nut 38, carried by the mandrel, will bear against the tapered portion 37; and, by this slackened weight, said nut will be held tightly within the tapered portion.

It is pointed out that the rods 32 are held against vertical movement by the ring 31, which is confined between the flange 30 and the lower end of the section 27. The section 11 will slide downwardly, moving the firing hammer 14 and the balls 35 downwardly therewith, until such time as the balls 35 are free to move back away from the hammer 14. At this time said hammer will be released. It is also pointed out that the friction blades 41 engage the casing and support the sections 26 and 27, and will act to hold said sections against any movement. It is further pointed out that when the mandrel 24 is rotated, the section 11, together with the rods 32 and the rest of the gun, except the sections 26 and 27 and the nut 38, will rotate due to the upper ends 75

of the rods 32 being connected to the ring 31 which will rotate within the flange 30. When the hammer 14 is released, the safety pin 43, having previously been removed before running the device into the well, will strike the exposed upper end of the plunger 47. The lower end of said plunger will strike the upper pin 53, striking the cartridge 54, exploding said cartridge, and firing the projectile out through the jacket 55 and the casing C. When said first pin strikes the cartridge, the explosion of said cartridge will act upon the next pin 53 and transmit that pressure to the next cartridge. This will be repeated until all of the shells have been fired. The tool may then be pulled out of the well, reloaded, inserted within the well, and fired again. It is specifically pointed out that the gun barrel, herein shown, is merely a means for carrying forth the invention, and that various other types of barrels could be used.

There is shown in Figures 7 and 8 another form carrying forth the principle of the hammer. Said hammer is very similar to the hammer shown in Figures 1 and 2. In this form, in place of the friction blades 41, there is provided a plurality of dogs 56 within the section 27; said dogs being pivotably mounted within the section 27 (Figure 9) and having an outwardly extending perpendicular edge 57. A spring 58 urges the 30 dogs outwardly so that they will engage the casing (not shown) at all times, but will not bite into said casing unless it is attempted to rotate the member 27 in a clockwise direction. At this time the biting edges 57 will bite into the casing and securely hold the section 27, and obviously section 26, from rotation, thereby allowing the rest of the structure to rotate identically with that shown in Figure 1.

The mandrel 24 is connected into the upper end of the section 11, and confined within the section 27, is the split nut 38 which rides within the taper 37. Said structure is provided with the rods 32, similar to the rods shown in Figures 1 and 2, which hold the balls 35 into engagement with the hammer 14, thereby preventing said hammer from moving downwardly. Provided in the lower end of the mandrel 24, and screw-threadedly attached thereto, is a flow bean 59. Said flow bean may be placed within said mandrel as desired, and is merely inserted within the mandrel when it is desired to flow the well through the structure. Due to the ports 23, similar to the ports shown in Figures 1 and 2, a flow bean would control the fluid passing into the device and up through the mandrel and the tubing.

It is pointed out that said well may be flowed through this structure, or the structure shown in the rest of the drawings, and may be left in the well until such time as the operator desires to remove the same; thus allowing the well to flow through the device without removing the same after the well casing has been perforated. In the forms shown in Figures 7 and 8, the hammer 14 is somewhat different from the hammer shown in Figures 1 and 2. It is provided with an upstanding collar 60 at its upper end and a cylindrical head 61 at its lower end. Said collar has a central recess 62, having its outer surface reduced and somewhat smaller than the head 61. Surrounding the head is a fluid packing ring 63, so that fluid may enter the chamber 13 and be sealed off, thereby preventing it from flowing down the lower end of the hammer. A coiled spring 64 is confined within the recess 62 of the

hammer and the top of the chamber 43. The head 61 is provided with a central screw-threaded opening 65 (Figure 11), which is provided above the packing ring 63 (Figure 7). An opening 65' also extends through the section 11. It is pointed out that the opening 65 through the section 11 is not internally screw-threaded. Insertable within said opening is a safety pin 66 which has its middle portion 67 externally screw-threaded. It is pointed out that said pin is considerably smaller than the openings 65 and 65', and is free to slide in and out of said opening when the hammer is held upwardly by the balls 35. Said pin may be held within said opening by a collar key 68, or any other suitable means.

In the event the balls 35 were left out, or became broken in transportation, the screw-threaded portion 67 of the pin 66 and the screw-threads of the pin 65 would engage due to the downward pressure of the spring 69. In an attempt to remove the pin, the threads would hold said pin, and the same could not be freely moved out of said opening. Thus, the operator would know that the pin was holding up said hammer, that some part had been left out of the gun, and that there was some difficulty within the firing mechanism. Thus, it can be seen that said pin acts as a safety feature and will not allow said hammer to be accidentally forced downward, which would result in the accidental firing of the gun. The pin 66 is usually left within the openings 65 and 65' until just before the gun is lowered into the well; thus, said gun is provided with a safety feature, and it may be transported without fear of the gun accidentally discharging.

As shown in Figures 7 and 8, the connection between the firing head and the gun barrel is slightly different from that shown in Figures 1 and 2. In Figures 1 and 2, the plunger is contained within the barrel; however, in the form shown in Figures 7 and 8, it is within the head, and the lower end of the section 11 is provided with an upstanding box 70. As will be noted in the drawings, the chamber 43 has its lower end open and screw-threaded opposite the screw-threads of the pin. The lower end of said chamber is closed by an external screw-threaded plug 71. Said plug is carried by the section 11 and is provided with an axial bore 72. The upper portion of said bore is enlarged and screw-threaded. Insertable within the enlarged screw-threaded portion 73, is a screw-threaded plug 74 which carries a firing plunger 75. Confined in the reduced portion of the bore 72 and the lower edge of the plug 74, is a cartridge 76, so that when the hammer is released, as explained hereinbefore and operating identically to that shown in Figure 1, it will strike the firing plunger 75, which will in turn strike the cartridge 76. Thus, the explosion of the cartridge is used to force the pins downwardly, as shown in Figure 2, or to operate this type of gun barrel.

The lower end of the plug 71 is reduced and forms a hexagonal head 77, so that said plug may be easily removed. It is pointed out that the head shown in Figures 7 and 8 operates identically to the head shown in Figures 1 and 2. The gun barrel, shown in Figures 1 and 2, may be attached thereto, or any other suitable gun barrel may be operated by either of said heads. In Figures 13 and 14, there is shown a means for firing a gun which does not depend upon rotation, however it does embody the hammer and locking structure, which will be herein explained. The gun barrel 44 may be connected to the lower

end of the firing head 78. The firing hammer 79 is very similar to the firing hammer 14, shown in Figures 2, 7 and 8. Said head 28 is provided with the chamber 80, and has its upper end reduced. The upper end of the head 78 is also reduced and externally screw-threaded to receive a running pipe or support 81. The firing head 78 is provided with diametrically opposite openings 82, extending from the chamber 80, and which have their outer ends internally screw-threaded. Screw-threaded plugs 83 close the outer ends of said openings.

The firing hammer 79 has an elongated upstanding collar 84 which is provided with an axial bore 85 therethrough. The collar 84 is provided with a plurality of openings 86. The upper end of the reduced portion of the bore 80 is reduced and forms a shoulder 87. Confined between the shoulder 87 and the upper end of the collar 84, is a coiled spring 88, so that said spring will exert a downward pressure upon the hammer at all times. Extending above the upper end of the head 78, and depending down into the bore 85 of the collar 84, is an elongate pin 89. The central portion 90 of said pin is reduced so that the lower end of the pin 91 and the upper end of the pin 89 are larger than the central portion 90. Said pin is held in the position shown in Figure 13 by a shear pin 92. Confined between the ends of the plugs 83 and the lower end 91 of the pin 89, are balls 93. As will be noted in the drawings, said pin holds the balls within the openings 86 of the collar 84; thus rigidly holding the collar and head 90 in their upward or firing positions.

The lower portion below the hammer is constructed identically to that shown in the previous figures, so that when said gun is desired to be fired, a tool 94, commonly referred to as a "go-devil", is dropped in the tubing. Said "go-devil" strikes the upper end of the pin 89, shearing the shear pin 92, and moving said pin downwardly. When the reduced portion 90 moves into alignment with the balls 93, they will snap inwardly and allow the spring 88 to push the hammer 79 downwardly, striking the firing plunger 75, and firing the gun. If it is desirable to produce after the head has been released, and the gun fired, it would only be necessary, before running the gun into the well, to provide a section of perforated pipe or screen above said head. Thus, the fluid from the strata could flow up around said head and through said perforations, and up the tubing.

It is pointed out that the firing head, herein described, may be operated in connection with various types of gun barrels, and would operate substantially the same as that shown in the previous figures.

Various changes, alterations and modifications may be made in the size, shape and arrangement of the herein described elements, within the scope of the appended claims.

What I claim and desire to secure by Letters Patent is:

1. In a well gun firing device, the combination of a gun barrel, a support having means for connecting with said gun barrel and provided with a chamber, a primary firing element movably disposed between the gun barrel and the chamber of said support, an actuating member movable in the chamber of said support, means for holding said member elevated above said firing element, means for running said device in a well bore, means set to operate from the top of the

well for releasing said holding means and firing said member when said running means is rotated, and means normally under tensioned restraint for impelling said member into firing engagement with said firing element.

2. The combination of a well gun barrel, of a firing device therefor including, means for running said device into a well bore, a firing element coacting with the firing means of the gun barrel, and means acting when the running means is rotated from the surface of the well for releasing said firing element which has been set before the device is run into the well.

3. The combination of a well gun barrel, of a firing device therefor including, a firing element coacting with the firing means of the gun barrel, means normally idle for actuating said firing element, and means acting when the running means is rotated from the surface of the well for releasing said firing element.

4. In a well gun firing device, the combination of a gun barrel, a support having means for connecting with said gun barrel and provided with a chamber, a firing hammer disposed within said chamber and above the gun barrel and movable downwardly, means for suspending said device in a well bore and means operable by rotation of the suspending means from the surface of the well for actuating said hammer.

5. In a well gun firing device, the combination of a gun barrel, a support having means for connecting with said gun barrel and provided with a chamber, a firing hammer normally locked in a cocked position, means for suspending said device in a well bore and means operable by rotation of the suspending means from the surface of the well for actuating said hammer.

6. In a well gun firing device, the combination of a gun barrel, a support having means for connecting with said gun barrel and provided with a chamber, means for holding a portion of said support against rotation, a firing hammer disposed and slidable within said chamber and above the gun barrel, means for suspending said device in the well bore, and means operable by rotation of the suspending means from the surface of the well for actuating said hammer.

7. In a well gun firing device, the combination of a gun barrel, a support having means for connecting with said gun barrel and provided with a chamber, a firing hammer disposed within said chamber and above the gun barrel, means for locking said hammer in its cocked position, tubular means for running and suspending said de-

vice within a well bore, and means for unlocking said hammer and firing said gun upon the rotation of the tubular suspending member.

8. In a well gun firing device, the combination of a gun barrel, a support having means for connecting with said gun barrel and provided with a chamber, means for holding a portion of said support against rotation, a firing hammer disposed and slidable within said chamber and above the gun barrel, tubular means for running and suspending said device within a well bore, and means for unlocking said hammer and firing said gun upon the rotation of the tubular suspending member.

15 9. In a well gun firing device, the combination of a gun barrel, a support having means for connecting with said gun barrel and provided with a chamber, a firing hammer normally locked in a cocked position, tubular means for running and suspending said device within a well bore, and means for unlocking said hammer and firing said gun upon the rotation of the tubular suspending member.

20 10. The combination with a well gun barrel having firing means, of a firing device including a firing element for engaging and actuating the firing means of the gun barrel, means for impelling said firing element, latch means engaging the firing element and holding it latched against movement by said impelling means, means for holding said latch means against operation, and means operable from the surface for running and suspending the gun and rotatable to release the latch holding means, whereby the latch is released and the firing element is freed.

25 11. In a well firing gun, the combination of a gun barrel, a head having means for connecting with and suspending said barrel and provided with a chamber, a firing hammer movable in said chamber above the gun barrel, means for suspending said device in a well bore and means in the head controlled by rotation from the surface of the well of the suspending means for operating said hammer.

30 12. A firing device for a well gun including, a head having means for suspending a gun barrel and provided in its lower portion with a chamber, a spring actuated hammer slidable in said chamber, latch means for fastening said hammer against movement, means for suspending said device in a well bore, and means operable by rotation of the suspending means at the surface of the well for releasing said latch means.

ARTHUR J. COLLINS.
